UNITED STATES PATENT OFFICE

HERBERT L. REDMAN, OF FOREST HILLS, NEW YORK, N. Y., ASSIGNOR TO SAKS & COMPANY, OF NEW YORK, N. Y., A CORPORATION OF NEW YORK

DESIGN FOR A LADY'S HANDBAG OR THE LIKE

Application filed April 18, 1932. Serial No. 43,528. Term of patent 14 years.

To all whom it may concern:

Be it known that I, HERBERT L. REDMAN, a citizen of the United States, residing at 132 Greenway North, Forest Hills, New York, N. Y., have invented a new, original, and ornamental Design for a Lady's Handbag or the like, of which the following is a specification, reference being had to the accompanying drawing, forming part thereof.

In said drawing: the figure is a front elevation of a handbag incorporating therein my new and ornamental design.

The reverse side of the bag is of the same design as that disclosed in the drawing.

I claim:

The ornamental design for a lady's handbag or the like, as shown and described.

HERBERT L. REDMAN.
